METHOD AND APPARATUS FOR REMOVING
SULPHUR AND PHOSPHORUS FROM MOL-
TEN METALS

Donald J. Campbell, Spring Lake, Mich.

Application May 20, 1942, Serial No. 443,774

9 Claims. (Cl. 266—34)

This invention relates, primarily, to the method and apparatus for removing sulphur and phosphorus from molten metals and, particularly the removal of sulphur and phosphorus from molten ferrous metal; and has for objects, first, the removal of sulphur from molten ferrous metal; second, the removal of phosphorus from molten ferrous metal; third, the removal of both sulphur and phosphorus from molten ferrous metal; fourth, the removal of such other impurities as can be separated from metals by centrifugal force while the metal is in a molten state; fifth, the general refining of molten metals, and particularly, ferrous metal.

These named objects and other objects are attained by the method described in the specification, and by the employment of the apparatus disclosed by the accompanying drawings, in which—

Figure 1 is a side elevation view of the apparatus by which the method of removing sulphur, phosphorus and the like, are removed from the molten metal; Figure 2 is a front end elevation view of the apparatus as it appears in readiness to put in operation; Figure 3 is a sectional view of the apparatus taken on a plane extending longitudinally of the apparatus from vertical line V, V, of Figure 2, and in which certain parts are shown in full line; Figure 4 is a cross-sectional view of the apparatus taken on line I, I, of Figure 1, and looking in the direction the arrow indicates; Figure 5 is a plan view of two of the resistor elements by which the lining of the apparatus is heated during the time the molten metal is not being operated upon, Figure 6 is a side view of one of the resistor heating units, and showing the ends bent and with a nut screw-threaded thereon. Figure 7 is a top plan view of the skimming apron which is hooked onto the front of the apparatus at the time of removing slag. Figure 8 is a top plan view of the electrical connector, by which connection is made for transmitting the electricity to the resistor heating units.

Similar numerals refer to similar parts of the apparatus throughout the several views of the drawings; and referring thereto:

Numerical 1 designates the concrete foundation upon which the base plate 2 supporting the apparatus is positioned. Numeral 3, the bearing vertically extending frame members comprising the support bearings 4 and 5, located at 6 and 7. These comprise in the preferred construction, bearing sleeves 8 and 9, that are drawn into the housings 10 and 11, and in which rotates the hol-

low shaft 12, supporting the barrel 13. The said barrel 13 consists of the structure comprising the cylindrical conical shell 14, having therein insulation lining 15, inside of which a fire brick lining 16, having therein an inner lining of specially shaped refractory blocks 17. Each of said blocks has its back in spaced apart relation to the interior of the liner periphery of the refractory block lining, one or more scallops 18 in which is held by fire clay the resistor heating units 19, having electrical connection with connector 20, an 20', or the bus rings 21 and 21' embedded in the refractory back 22. The said connectors extend through the refractory back 22, and through the back plate 23 of the shell 14, from which the connectors are insulated by insulating sleeve 24. They are engaged by electrical contact members 25 and 25', of which there is one for each pair of terminals of the resistor heating units, both of which are supported by insulating block 26, secured to carriage 27. Slideways 28 are secured to the bearing housing at 29, and slidable in relation thereto, by adjusting screw 30 turned by hand wheel 31, to slide the carriage 27 for making and breaking contact with the connectors 20 and 20'. Cables 31 and 32 conduct electricity to the contact members 25 and 25'. These have connection therewith made by terminal members 33 and 34, secured to the contact members by headed screws 35. At the front of the shell 14 is molten metal tapping out hole 36, closed by botting clay plug 36', in front of which is spout 37. They comprise the metal shell 38, having upwardly extending flanges 39, with lug 40 extending toward the front of the shell 14. Under this is placed the botting clay plug locking bar 41, engaging screw-threaded bar 42, which is there holding the botting plug in the hole 36, and thereby preventing the plug being forced out of the hole 36 by the molten metal. The spout shell 38 has refractory lining 43, whereby the shell is prevented from being melted by the molten metal as it is tapped from the barrel. At the front of the barrel 13 is inwardly extending flange 44, for holding the refractory lining 45 in place, and through which at the axis of the barrel 13, extends skim hole 46 having flattened portion 47, for increasing the capacity of the barrel when the barrel is at rest, over what it would be had there been no flat and the hole were cylindrical. The flat also provides a support for the scraper employed in skimming slag from the top of the molten metal. This skim hole 46 is always closed during processing of the metal by the rotatable seal-

ing head 48, which is provided with an air insulating chamber 49, and composition insulating member 50. The head 48 has trunnion 51, extending axially from its side farthest removed from its face 52, for rotatably supporting the head around the periphery of which extends annular packing 53, for preventing air entering the barrel during processing of the molten metal. Numeral 54 refers to a sealing plate secured to the inwardly extending flange 44 of the shell 14, and engaging the packing 53. The trunnion 51 of the head 48 is supported by, and rotatable in bearing 55, provided with anti-friction rollers 56, rotatable in housing 57, where they are retained by flange 58 having a portion 59, screw-threaded in the hole in the trunnion 51. The bearing housing 57 is of semi-spherical form, and is socketed in concave cup 61 of the arm 62, extending from and forming a part of vertically extending column 63. This column 63 has supporting hinge lugs 64, extending from its back, with pivot pins 65 extending downward therefrom, through bearings 66 of brackets 67, secured to I beams, for swingably supporting the column 63, arm 62, and parts associated therewith. The annular collar 68, which is shaped at one of its sides to the contour of the semi-spherical portion of the bearing housing, retains the bearing housing in the concave cup 61.

Encircling the shell 14 at its front portion, is annular track 73, engaged by rollers 74, rotatably mounted in suitable bearings carried by supporting saddle bracket 75. The said bracket 75 has portions extending in a curve part way up each side of the barrel 13. Each portion has hinged thereto as, by pins 76, inwardly curved arms 77 and 77', each carrying roller 78 rotatable on bearing pin 79. One of said arms having lugs 80 to which is pivotally connected by pin 81, eye bolt 82 which has screw threaded shank 83 surrounded by spring 84, secured to the shank by nut 85, whereby tension of the spring may be set. The spring 84 at its end farthest removed from the nut 85, engages washer 86 resting against slotted lug 87, extending upward from the end of the arm 77'. The purpose of this spring arrangement is to bring the rollers 78 forcibly against the annular track 73, and against which they roll. Its purpose being to prevent the track 73 leaving the rollers 74, while at the same time by the give of the helical spring 84, allowing the track to expand without binding. Adjacent the refractory back 22, is refractory lining 22', having a recess 23' into which is set porous refractory block 23'', for preventing molten metal being drawn to the air pump through tube 99.

At the rear or smaller end of the barrel shell 14, and secured thereto, is spider 88, integral with the hollow shaft 12, which is provided with an insulating chamber 89, and longitudinally extending bore 90. This chamber is closed against entrance of air thereto by packing 91, consisting of annular disc 92 secured to the end of the hollow shaft 12 and rotatable therewith. This stationary annular flange 93 has hub 94, extending into and secured to the housing 95, extending from and forming a part of the suction pipe 96, the open top of which is vacuum control closing valve 97. This is provided with operating lever 98. Extending longitudinally of the bore 90 of the hollow shaft, and supported therein by the hub 94, is hollow tube 99 of high heat resisting metal, or of a suitable refractory. The lower end of the pipe 96 is connected to the air pump 100 75

driven by belts 101, engaging grooved pulley 102 on the pump shaft, and the grooved pulley 103 of the hollow shaft 12. The said grooved pulley 103 is also engaged by drive belts 104, engaging the 5 grooved pulley 105, on the shaft of the drive motor 106, provided for operating the apparatus. Also secured to the hollow shaft 12 is brake drum 107. This is engaged by brake band 108, operated when applying brake by any suitable means for 10 turning the screw 110, rotatably supported by bracket 111, secured to the frame of the apparatus. The spider 88 has diametrically opposite the connector members 20, a notch 112 into which dog 113 of the slidable rack 114 extends, and is 15 operated by gear pinion on the shaft 115, on the shaft of the hand wheel 116. By this the said gear can be turned, and in so doing slide the rack 114 upward, and thereby the dog 113 into engagement with the said notch of the spider. 20 The said notch is so located that the drum will be held in such position, that the flattened portion of the hole 46 will be extending horizontally below the axis of the drum.

Just previous to tapping the molten metal from 25 the barrel 13, it is necessary to draw or skim the slag and dross from the top of the molten metal. This is done by a suitable skim bar extended into the barrel through the hole 46. This slag or dross is of a thick syrupy nature, and unless prevented 30 would fall on the spout 37 when skimming, and prevent flow of the molten metal. Therefore, skim apron 118 is provided, having upward projecting side ribs 119 and hook like projections 120, whereby the apron is applied to the front 35 plate 54 of the barrel, by extending the projections into the elongated holes 121, extending through plate 54 and flange 44, at a higher level than the spout 37.

In carrying out the method of my invention, I 40 provide an apparatus substantially as described. Molten metal having a temperature exceeding 2800 degrees Fahrenheit, is deposited in the barrel 13, through the hole 46. When sufficient of the molten metal is deposited to bring its top 45 surface of the metal almost to the surface of the flattened side 47 of the hole 46, extending through the front of the barrel when the barrel is at rest, the sealing head 48 is swung away from in front of the hole. When the molten 50 metal has been deposited in the barrel, I swing the arm 76, and thereby the sealing head against the front sealing plate 54 of the barrel, after which I start the motor 106, and thereby rotate the barrel 13 and the molten metal therein. By 55 starting the said motor and barrel, the air pump is started also, and by its connecting pipe 96 and tube 99 extending and open to the interior of the barrel, draw a partial vacuum within the barrel and on the molten metal therein, which when 60 the barrel is first started the molten metal is carried upward at the rising side of the barrel by the refractory lining blocks 11, and rolls back in an endeavor to level off until sufficient rotational speed is reached, which for a barrel having 65 a six foot internal diameter the speed should approximate 200 revolutions per minute. At this speed the molten metal by the centrifugal force, is distributed over the entire inner circumference of the lining, and will have a substantially uniform 70 inner thickness. The first tumbling or sliding back of the molten metal as the barrel starts to rotate, churns and mixes the metal, thereby working the lighter impurities from the molten metal to its inner periphery, and where 75 the solid impurities can be skimmed off. When

the rotative speed of approximately 200 revolutions per minute is reached, substantially all sulphur and phosphorus is squeezed out of the molten metal by centrifugal force, and drawn from the barrel by suction formed by the air pump. When the sulphur and phosphorus which are in a gaseous state in the center of the revolving mass, are drawn from the barrel by the air pump and discharged into the atmosphere, the vacuum control valve 97 is opened, but during processing the metal the valve is employed to regulate the amount of vacuum.

Having described my invention, the rights it is desired to secure are disclosed in the hereinafter named claims, and I claim:

1. Apparatus for removing sulphur and phosphorus from molten metals, comprising a conical shell of wrought metal having a back at its smaller end, and an inwardly extending flange at its larger end, with a semi-circular hole at its axis having a flattened side, the shell having a lining of heat insulating material, a second lining of refractory blocks each having a recess with a portion of an electrical heating unit therein, having a connector extending exterior of the shell for engaging an electrical contact member connected to an electrical circuit, and a third lining of refractory blocks within the said second lining, the said inwardly extending flange front of the shell having a refractory lining with a tap out hole at the inner periphery of the shell lining, and in radially spaced apart relation to the flattened side of the hole at the axis of the inwardly extending flange front, and having a spout extending from adjacent the said tap out hole for conveying the molten metal away from the said tap out hole, a skim 'apron adapted to be attached to the front of the shell between the flat side of the skim hole at the axis of the inwardly extending flange and the said tap out hole, a hollow shaft extending axially from the back of the said shell, and rotatable in bearings supporting an end of the shell and refractory lining therein, a dog latch engaging the back of the shell for preventing rotation of the shell during the skim and tap out periods of the molten metal within the lining of the said shell, the said dog latch forming a part of a slideable rack moved by a gear rotated by a hand wheel, a tubular member extending longitudinally of and within the said hollow shaft, and supported by a hollow head having connection with a pipe connected to an air pump, for drawing a partial vacuum in the said shell, and a valve associated with the said pipe for breaking the said partial vacuum.

2. Apparatus for removing sulphur and phosphorus from molten metals, comprising a conical shell of wrought metal having a back at its smaller end, and an inwardly extending flange at its larger end, with a semi-circular hole at its axis having a flattened side, the shell having a lining of heat insulating material, a second lining of refractory blocks each having a recess with a portion of an electrical heating unit therein, having a connector extending exterior of the shell for engaging an electrical contact member connected to an electrical circuit, the said inwardly extending flange front of the shell having a refractory lining with a tap out hole at the inner periphery of the shell lining, and in radially spaced apart relation to the flattened side of the hole at the axis of the inwardly extending flange front, and having a spout extending from adjacent the said tap out hole for conveying the molten metal away from the said tap out hole, a

hollow shaft extending axially from the back of the said shell and rotatable in bearings supported by the apparatus, a dog latch engaging the back of the shell for preventing rotation of the shell, during the skim and tap out periods of the molten metal within the lining of the said shell, a tubular member extending longitudinally of and within the said hollow shaft, and extending into a hollow head having connection with a pipe connected to an air pump for drawing a partial vacuum in the said shell.

3. Apparatus for removing sulphur and phosphorus from molten metals, comprising a conical shell of wrought metal having a back at its smaller end, and an inwardly extending flange at its larger end, with a semi-circular hole at its axis having a flattened side, the shell having a lining of heat insulating material, and a second lining of refractory blocks each having a recess with a portion of an electrical heating unit therein, having a connector extending exterior of the shell for engaging an electrical contact member connected to an electrical circuit, the said inwardly extending flange front of the shell having a refractory lining with a tap out hole at the inner periphery of the shell lining, and in radially spaced apart relation to the flattened side of the hole at the axis of the inwardly extending flange front, and having a spout extending from adjacent the said tap out hole for conveying the molten metal away from the said tap out hole, a hollow shaft extending axially from the back of the said shell and rotatable in bearings supported by the apparatus, a dog latch engaging the shell for preventing rotation of the shell during the skim and tap out periods of the molten metal within the lining of the said shell, a tubular member extending longitudinally of and within the said hollow shaft, and extending into a hollow head having connection with a pipe connected to an air pump for drawing a partial vacuum in the said shell.

4. Apparatus for removing sulphur and phosphorus from molten metals, comprising a conical shell of wrought metal having a back at its smaller end, and an inwardly extending flange at its larger end, with a semi-circular hole at its axis having a flattened side, the shell having a lining of heat insulating material, a second lining of refractory blocks each having a recess with a portion of an electrical heating unit therein, and having a connector extending exterior of the shell for engaging an electrical contact member connected to an electrical circuit, the said inwardly extending flange front of the shell having a refractory lining with a tap out hole at the inner periphery of the shell lining, and in radially spaced apart relation to the flattened side of the hole at the axis of the inwardly extending flange front, and having a spout extending from adjacent the said tap out hole for conveying the molten metal away from the said tap out hole, a hollow shaft extending axially from the back of the said shell and rotatable in bearings supporting an end of the shell by the apparatus, a tubular member extending longitudinally of and within the said hollow shaft, and supported at one of its ends by a hollow head having connection with a pipe connected to an air pump for drawing a partial vacuum in the said shell.

5. Apparatus for removing sulphur and phosphorus from molten metal, having a refractory lined conical shell, including a back and a front, the said front having a tap out hole for removing molten metal from the interior of the shell lining,

and a flattened sided hole through which to skim the molten metal, a hollow shaft extending axially from the back of the shell and rotatable in bearings supporting an end of the shell, a tubular member extending longitudinally of and within the said hollow shaft, and an air pump having connection with the said tubular member for drawing a partial vacuum at the interior of the conical shell, and means for starting and accelerating rotation of the shell having molten metal therein.

6. Apparatus for removing sulphur from molten metal, having a refractory lined conical shell including a back, and a front having a tap out hole for removing molten metal from the interior of the shell, a flattened hole at the axis through which to skim the molten metal, a hollow shaft extending axially from the back of the shell, and rotatable in bearings supporting an end of the shell by the apparatus, a tubular member extending longitudinally of and within the said hollow shaft, and an air pump having connection with the said tubular member for drawing a partial vacuum at the interior of the conical shell, and means for starting and accelerating rotation of the shell having molten metal therein.

7. Apparatus for removing phosphorus from molten metal, having a refractory lined conical shell including a back, and a front having a tap out hole for removing molten metal from the interior of the shell lining, and a flattened hole through which to skim the molten metal, a

hollow shaft extending axially from the back of the shell, and rotatable in bearings supporting a portion of the conical shell by the apparatus, a tubular member extending longitudinally of and within the said hollow shaft, and an air pump having connection with the said tubular member for drawing a partial vacuum at the interior of the conical shell.

8. Apparatus for removing sulphur from molten metal, having a refractory lined conical shell including a back, and a front having a tap out hole for removing molten metal from the interior of the shell lining, and a hole through which to skim the molten metal, a hollow shaft extending axially from the back of the shell and rotatable in bearings supporting the shaft, a tubular member extending longitudinally of and within the said hollow shaft, air pump having connection with the said tubular member for drawing a partial vacuum at the interior of the conical shell, and means for rotating of the shell having molten metal therein.

9. In the invention comprising improvements in removing sulphur and phosphorus from molten metal, an apparatus having a refractory lined rotatable barrel, having a skim hole at one of its ends and a hollow supporting shaft extending from the opposite end through a pair of bearings, with means on the shaft for rotating the shaft and barrel and means for applying suction to the interior of the barrel through the hollow shaft.

DONALD J. CAMPBELL.
